UNITED STATES PATENT OFFICE.

FRANK V. EASTMAN, OF ST. PETERSBURG, FLORIDA, ASSIGNOR OF ONE-TWENTIETH TO ALICE M. BALLENGER AND ONE-TWENTIETH TO ARTHUR G. EASTMAN, BOTH OF ST. PETERSBURG, FLORIDA, AND THREE-FOURTHS TO FRED R. EASTMAN, OF GRAND RAPIDS, MICHIGAN.

IGNITION DEVICE FOR INTERNAL-COMBUSTION ENGINES.

1,181,122.

Specification of Letters Patent.

Patented May 2, 1916.

Application filed June 15, 1914. Serial No. 845,121.

To all whom it may concern:

Be it known that I, FRANK V. EASTMAN, a citizen of the United States, and a resident of St. Petersburg, in the county of Pinellas 5 and State of Florida, have made certain new and useful Improvements in Ignition Devices for Internal-Combustion Engines, of which the following is a specification.

My invention relates to improvements in 10 ignition devices for internal combustion engines, and it consists in the constructions, combinations, and arrangements herein described and claimed.

An object of my invention is to provide 15 a device by means of which cheaper fuel oils for operating internal combustion engines may be used without the usual ignition troubles heretofore arising from the use of such fuels.

20 A further object of my invention is to prevent the deposit of carbon which ordinarily occurs in internal combustion engines of the common type.

25 A further object of my invention is to provide means for preventing the disastrous effects of moisture upon the ignition system.

Other objects and advantages will appear 30 in the following specification and the novel features of the device will be particularly pointed out in the appended claims.

My invention is illustrated in the accompanying drawing forming part of this application in which the figure is a central section through the device, showing its application 35 to the cylinder of an internal combustion engine.

In carrying out my invention I provide a spherical casing having an external wall 1 and an internal wall 2 spaced apart from the 40 wall 1 to provide a water jacket or an oil vaporizing jacket 3, depending upon the manner in which the device is used. The spherical casing is provided with a threaded extension 4 which is arranged to enter the 45 threaded opening 5 in the cylinder 6, this opening being the one generally used for insertion of the ordinary spark plug.

The spherical casing has a laterally extending threaded portion 7 which is arranged to receive a spark plug 8 of any 50 suitable type. A cylindrical extension 9 is also threaded to receive a body portion 10

of an auxiliary fuel intake which will be described in detail hereinafter.

As will be seen from the drawing the extension 4 is hollow and communicates with the interior 11 of the spherical casing. A valve member 12 is arranged to seat at the bottom of the extension 4. This valve member is carried at the bottom of a hollow cylindrical stem 13 which passes upwardly through the hollow extension 4, through a central guide member 14 which extends part way into the chamber 11, and communicates at its top with a T-shaped valve casing 15. The latter is provided with a needle valve 16, which may be set by a knurled head 17 and secured in its adjusted position by means of a lock nut 18. The needle valve 16 controls an inlet port 19. A slip-nipple joint 20 furnishes means of attachment of a flexible conduit 21. The valve 12 is held normally in closed position by means of a spring 22 which bears at one end on a cap 23 carried by the casing and at the other 25 end on an adjustable nut 24 having a companion lock nut 25. A portion of the valve stem 13 is threaded to accommodate these nuts.

The auxiliary fuel intake comprises the 30 body portion 10 mentioned heretofore to which is screwed a casing member 25 having an inlet 26. This casing member is provided with an inwardly extending guide member 27 having a stem 28 which bears 35 at its inner end a valve 29, arranged to engage a valve seat 30 at the end of the member 10. As will be seen from the drawing the valve stem 28 has an enlarged portion 31 which is provided with radially extending openings 32 leading from the interior 40 of the valve stem. A spring 33 is disposed on the interior of the valve stem and bears at one end on a screw plug 34 and at the other on a ball valve 35, which is adapted 45 to close the hollow stem 28. The outer end of the stem 28 communicates with a valve casing 36 which has a needle valve 37 arranged to govern an intake port 38. A spring 39 bears at one end on the casing 50 member 25 and at the opposite end on the adjustable nut 40 which is provided with a companion lock nut 41.

From the foregoing description of the

various parts of the device the operation thereof may be readily understood.

In the drawing I have indicated the power expansion area of the cylinder by A 5 and the piston by P. Fuel is designed to be introduced into this power expansion chamber A direct from the carburetor, as in engines of the ordinary type. This fuel, however, may be of a lower grade than that 10 which is ordinarily necessary. It may be a mixture of gasoline, kerosene, distilled or crude oil, vapor and air, or oxygen in combustible proportions, or it may be a gas such as natural fuel gas or illuminating 15 gas with air and moisture in combustible proportions, or it may be a mixture of any of these combustible combinations overcharged with air and of slow burning temper. When the latter fuel is used an additional fuel adjustment may be made by introducing the fuel through the hollow stem 13.

The auxiliary fuel may be introduced 20 through the inlet 38, which is regulated by the needle valve 37. This fuel may be alcohol, gasoline, acetylene gas, or other suitable fuel, either under pressure or gravity feed. Air is designed to enter the inlet 25 to combine with the fuel in combustible proportions.

Let us assume that the engine takes its 30 intake stroke. This will open the valve 12 against the tension of the spring 22 and will cause a vacuum in the interior of the spherical casing 2 whereupon the valve 29 will become unseated, thus permitting the fuel 35 to pass the ball valve 35 and through the passages 32 where it will combine with the air coming through the inlet 26 and will 40 thus enter the chamber 11 as a combustible gas or vapor. On the compression stroke of the engine the fuel already in the explosion chamber A is compressed. At the proper time the spark passes between the 45 terminal of the spark plug 8 and this mixture is exploded. This charge I term the percussion charge, since explosion automatically opens the valve 12 and ignites the gas in the expansion area A. The provision 50 of a combustible gas which is already ignited insures the positive ignition of the gas in the power area A, even though the latter may be of such composition as would not ordinarily ignite by the passage of the 55 electric spark.

It will be understood that the percussion 60 charge opens the valve 12 early in the explosion. That is to say the gas is still burning as it passes into the power area. This not only tends to ignite the gas in the power 65 area by direct contact of the burning gases, but it also increases the compression in the power area and tends to bring it nearer to the point where gas in the power area will ignite under compression alone.

It will be noted that this device acts in fact as an auxiliary carburetor. That is to say, the mixture of the air and fuel of the percussion charge takes place after the valve 29 is opened, this mixture being effected within the chamber 11 in which the spark plug 8 is located.

I claim:

1. In an ignition device for internal combustion engines, a double wall casing having a threaded extension arranged to enter the spark plug opening of a cylinder, said casing having laterally extending threaded extensions, a spark plug carried by one of said laterally extending threaded extensions, an inlet plug carried by the other laterally extending threaded extension, said inlet plug being provided with a movable hollow valve stem having laterally extending openings and being provided at its end with a valve arranged to engage the end of the plug, means for introducing air around said hollow stem, a valve disposed within the cylinder of the engine and having a hollow stem, and means connected with said last named hollow stem for introducing fuel into the interior of the engine.

2. In an ignition device for internal combustion engines, a double wall casing having a threaded extension arranged to enter the spark plug opening of a cylinder, said casing having laterally extending threaded extensions, a spark plug carried by one of said laterally extending threaded extensions, an inlet plug carried by the other laterally extending threaded extension, said inlet plug being provided with a movable hollow valve stem having laterally extending openings and being provided at its end with a valve arranged to engage the end of the plug, means for introducing air around said hollow stem, a valve disposed within the cylinder of the engine and having a hollow stem, means connected with said last named hollow stem for introducing fuel into the interior of the engine, and spring means for regulating the tension of the last named valve.

3. In an ignition device for internal combustion engines, a double wall casing having a threaded extension arranged to enter the spark plug opening of a cylinder, said casing having laterally extending threaded extensions, a spark plug carried by one of said laterally extending threaded extensions, an inlet plug carried by the other laterally extending threaded extension, said inlet plug being provided with a movable hollow valve stem having laterally extending openings and being provided at its end with a valve arranged to engage the end of the plug, means for introducing air around said hollow stem, a valve disposed within the cylinder of the engine and having a hollow stem, means connected with said last named

hollow stem for introducing fuel into the interior of the engine, spring means for regulating the tension of the last named valve, and means for locking the tension adjusting means of the last named valve.

- 5 4. In an ignition device for internal combustion engines, a double walled casing having a threaded extension arranged to enter the spark plug opening of the engine cylinder, said casing having laterally extending threaded extensions, a spark plug carried by one of said laterally extending threaded extensions, an inlet plug carried by the other laterally extending threaded extension, said inlet plug being provided with a movable hollow valve stem having laterally extending openings and being provided at its end with a valve arranged to engage the end of the plug, spring means for holding 10 said valve normally against the plug, passages in said inlet plug for introducing air around said hollow stem, a valve disposed within the cylinder of the engine and having a hollow stem, and means connected 15 with said last named hollow stem for introducing fuel into the interior of the engine.
- 20 5. In an ignition device for internal combustion engines, a double walled casing having
- 25

ing threaded extensions arranged to enter the spark plug opening of the engine cylinder, said engine having laterally extending threaded extensions, a spark plug carried by one of said laterally extending threaded extensions, an inlet plug carried by the other laterally extending threaded extension, said inlet plug being provided with a movable hollow valve stem having laterally extending openings and being provided at its end with a valve arranged to engage the end of the plug, spring means for holding said valve normally against the plug, passages in said inlet plug for introducing air around said hollow stem, a valve disposed within the cylinder of the engine and having a hollow stem, means connected with the said last named hollow stem for introducing fuel into the interior of the engine, spring means for regulating the tension of the last named valve, and a lock-nut for locking the spring adjusting means of the last named valve in 40 45 50 position.

FRANK V. EASTMAN.
